(57) **CLAIM**

The ornamental design for a surgical guide, as shown and described.

DESCRIPTION

FIG. 1 is a perspective view of a surgical guide, showing our new design;

FIG. 2 is a front elevation view of the surgical guide illustrated in FIG. 1;

FIG. 3 is a rear elevation view of the surgical guide illustrated in FIG. 1;

FIG. 4 is a right elevation view of the surgical guide illustrated in FIG. 1;

FIG. 5 is a left elevation view of the surgical guide illustrated in FIG. 1;

FIG. 6 is a top plan view of the surgical guide illustrated in FIG. 1; and,

FIG. 7 is a bottom plan view of the surgical guide illustrated in FIG. 1.

The broken lines in the drawings show portions of the surgical guide that form no part of the claimed design.

1 Claim, 7 Drawing Sheets
